UNITED STATES PATENT OFFICE

IRVING STEINHARDT, OF NEW YORK, N. Y.

CARBURETOR

Application filed August 9, 1930. Serial No. 474,184.

This invention relates to an improvement in carburetor for explosive engines.

In engines used for driving automobiles and the like it is a known fact that when the automobile is travelling at good speed along a level highway the explosive mixture furnished by the carburetor may advantageously be considerably leaner than when the engine is operating at slower speeds or when driving the vehicle up an incline, also that where the carburetor of the engine feeds its gasoline into the air blast through an aperture of a given size the resultant mixture of air and gas is relatively leaner at low speeds than at higher speeds.

It is an object of the present invention therefore to provide simple, practical and efficient means for causing the mixture to be automatically made leaner in proportion to increasing speed of the engine.

A further object is to provide means for temporarily enrichening the mixture delivered by the carburetor whenever the throttle is moved toward open position.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawing which is to be taken as a part of this specification, and in which I have shown merely a preferred form of embodiment of the invention, there is illustrated a diagrammatic view of a carburetor device embodying this invention and showing the same in operative association with an explosive engine.

Referring to the drawing for describing in detail the exemplary structure illustrated therein, the reference character L indicates the intake manifold of an ordinary explosive engine G.

The carburetor, indicated generally by the reference character H, includes the usual gasoline reservoir 1 containing the float 2 for keeping the gasoline level constant within the

gasoline jet 3. The jet 3 is arranged within the Venturi tube 4 which communicates with the passage 5 within which is arranged the throttle valve 6.

Gasoline enters the reservoir 1 through a tube as 7, and a supply of air enters through a pipe as 8 which communicates with the bottom end of the Venturi tube.

The usual operating rod 9 is connected with the throttle valve, as by means of the radial arm 10 fixed to the shaft of said valve for manually controlling the movements of the throttle valve in the customary way.

Whenever the throttle valve 6 is rotated open to admit a larger volume of explosive mixture into the cylinders for accelerating the speed of the engine the increased speed of the pistons causes the blast of air surging around the jet 3 within the Venturi tube to be increased in velocity thereby tearing off from the jet relatively more gasoline, proportionate to the volume of air passing in a given period, than was torn off at the lower speed at which the engine had been previously running.

The increase in proportion of gas to air would continue to grow greater progressively unless means be provided to prevent it.

To this end the present invention proposes the use of a gasoline needle 11 or other suitable means arranged for controlling the amount of gasoline which may pass out of the jet 3 under differing conditions. For convenience of illustration the needle 11 is herein shown to be directly within the gasoline jet and to be longitudinally slidably mounted to move toward and away from the jet orifice 12. When this needle is in a relatively lower position the orifice 12 will be relatively unobstructed so that gasoline may pass freely therethrough in the customary manner, but when the needle is raised it will obstruct the orifice more or less according to the degree to which the needle is raised.

The lower portion of the needle extends slidably through the bottom wall portion 13 of the jet and a projecting part as 14 rests upon the upper surface of an actuating member 15. A spring 16 is illustrated for urging

the needle always downwardly against the actuating member.

The actuating member is pivotally connected by one of its ends as at 17 with a lever 18 which in turn is pivotally mounted as at 19 upon the wall of the carburetor and extends upwardly into co-operative relation with an arm 20 fixed to the shaft of the throttle valve.

The opposite end of the actuating member is provided with a beveled surface 21 at its underside which rests upon the correspondingly bevelled upper surface 22 of a slide member 23. The slide member 23 is mounted to slide horizontally in a suitable support as 24 and is adapted to be slid through the action of a governor device 25 driven by a shaft 26 which is coupled with a moving part of the engine G, for instance the main drive shaft 27 of said engine, through a drive belt at 28.

The operation of this mechanism is as follows: It being noted that the position of the slide 23 with respect to the actuating member 15 is always determined by the speed of the engine and that the position of the actuating member is in turn always dependent upon the position of the throttle valve. Whenever the throttle valve is operated toward open position the arm 20 will swing the lever 18 about its pivot and cause the actuating member to move horizontally toward the right, in the drawing. Owing to the fact that the actuating member rests upon the inclined surface 22 of the slide 23 its movement to the right will be accompanied by a slight downward swing about the pivot 17 thereby lowering the gasoline needle 11 away from the orifice 12 so that an ample quantity of gasoline may move through said orifice for suitably enrichening the air blast passing through the Venturi tube at this moment.

If at this time the automobile be assailing the task of climbing an incline so that the speed of the engine will not be accelerated the increased charge of gasoline will be beneficial in enabling the engine to develop the required power for accomplishing its appointed task.

If on the other hand the grade is only slight, or none is present, so that the speed of the engine may be accelerated, then the acceleration of speed being transmitted to the governor device 25, will cause the slide 23 to move to the right, in the drawing, and its inclined surface 22 to raise the actuating member and lift the gasoline needle 11 to a degree dependent upon the extent of acceleration and increasing progressively as the acceleration increases. The orifice 12 will be closed proportionally and the mixture correspondingly reduced in richness as the speed increases.

If a hill be encountered while the engine is running at high speed, as just indicated, so that the speed of the engine diminishes, then the slowing down of the governor device 25 will allow the needle 11 to move further

open and thereby provide a suitably enlarged passage-way through the orifice 12 calculated to afford just the correct strength of mixture for the particular task being performed by the engine.

As many changes could be made in this construction without departing from the scope of the invention as defined in the following claims, it is intended that all matter contained in the above description, or shown in the accompanying drawing, shall be interpreted as illustrative only and not in a limiting sense.

Having thus described my invention, what I claim as new and desire to secure by Letters Patent is:

1. A carburetor comprising means providing an air passage, a gasoline jet within said air passage, a throttle valve, a control member for determining the outlet size of the gasoline jet, a speed controlled governor device having means by which it may be driven from the engine shaft, and connections between the throttle valve, the governor device and said control member to operate the control member in response to both the movements of the throttle valve and the speed of the engine, and add said connections including a pair of movable wedge acting parts having relatively inclined surfaces engaging against each other one of said parts being connected to be moved in response to movements of the throttle valve and the other of said parts being connected to be moved in response to operation of the governor device.

2. A carburetor comprising means providing an air passage, a gasoline jet within said air passage, a throttle valve, a control member for determining the outlet size of the gasoline jet, a speed controlled governor device having means by which it may be driven from the engine shaft, spring means urging the control member toward open position, an actuating member for said control member, a lever connected between said actuating member and the throttle valve operable to permit movement of the control member by said spring means toward open position by opening movement of the throttle valve, and connections between the governor device and said actuating member operable to effect movement of the control member against the pressure of said spring means toward closed position in consequence of an increase in speed of the engine shaft.

3. A carburetor comprising means providing an air passage, a gasoline jet within said air passage, a throttle valve, a control member for determining the outlet size of the gasoline jet, a speed controlled governor device having means by which it may be driven from the engine shaft, and connections between the throttle valve, the governor device and said control member to operate the control member in response to both the movements of the

throttle valve and the speed of the engine, said connections including a pair of movable wedge acting parts having relatively inclined surfaces slidably engaging against each other, one of said parts being connected to be moved in response to movements of the throttle valve and having connection with the control member to in turn move the control member in response to movements of the throttle valve, said mentioned part being also movable to move the control member independently of movement of the throttle member, the other of said parts being connected to be moved in response to operation of the governor device, and the slidably engaging inclined surfaces of said two parts being disposed to effect movement of the first part and of the control member from the governor device independently of movement of the throttle member.

4. A carburetor comprising means providing an air passage, a gasoline jet within said air passage, a throttle valve, a control member for determining the outlet size of the gasoline jet, a speed controlled governor device having means by which it may be driven from the engine shaft, and connections between the throttle valve, the governor device and said control member to operate the control member in response to both the movements of the throttle valve and the speed of the engine, said connections including a pair of relatively movable parts one connected to be moved in response to movements of the throttle valve and having engagement with the control member to in turn move the control member in response to movements of the throttle valve, said mentioned part being also movable to move the control member independently of movement of the throttle valve, and the other of said parts being connected to be operated by the governor device and having engagement with the first part to move the first part in a manner to effect movement of the control member independently of movement of the throttle valve.

5. A carburetor comprising means providing an air passage, a gasoline jet within said air passage, a throttle valve, a control member for determining the outlet size of the gasoline jet, a speed controlled governor device having means by which it may be driven from the engine shaft, an actuating member for said control member, a movable member with which said actuating member slidably engages, said actuating member and said movable member having co-operative wedge acting surfaces slidably engaging together, connections between the actuating member and the throttle valve by which to slide the actuating member for moving the control member in response to operation of the throttle valve, and connections between said movable member and said governor device whereby operation of the governor device will move

said movable member with respect to said actuating member for thereby causing the wedge acting surfaces of said movable and actuating members to effect a movement of said actuating member and a consequent movement of said control member independently of movement of said throttle valve.

In testimony whereof I affix my signature.
